UNITED STATES PATENT OFFICE.

HARVEY GILES, OF BROOKLYN, NEW YORK, ASSIGNOR TO ARTEMAS WARD, OF NEW YORK, N. Y.

COIN-CONTROLLED VENDING MACHINE.

Application filed June 22, 1922. Serial No. 570,100.

To all whom it may concern:

Be it known that I, HARVEY GILES, a citizen of the United States, and a resident of Brooklyn, in the county of Kings and State 5 of New York, have invented certain new and useful Improvements in Coin-Controlled Vending Machines, of which the following is a specification.

The invention pertains to means arranged 10 at the coin entrance slot of a coin-controlled machine, as, for illustration, a vending machine, for arresting a washer, or a coin or a disk with a hole in it, so that the same may not pass into the interior mechanism of the 15 machine, but which nevertheless may be withdrawn outwardly from said arresting means and from the coin-slot so as to leave said coin-slot free for the entrance of proper coins. The new mechanism provided by me is located at the inner or reverse 20 face of the coin-slot plate of the machine and at the inner end of the entrance slot therein for coins.

The washer arresting means of my invention belongs to the class of devices commonly applied to vending and other coin-controlled machines and designated as "washer catchers", and the device or washer catcher of my invention is preferably constructed 25 of two members hinged together and a leaf-spring, one of said members being an elongated actuating arm having thereon a stop-lug which engages the other member and serves to keep said members, when in 30 their normal condition, properly spaced apart at the outer or operative portions of the same, and the other of said members being a washer catcher-arm normally extending lengthwise along a portion of the 35 coin-slot and having a right angular prong or dog normally lying at one side of the coin-slot and at about the transverse middle line thereof and adapted to be projected across said slot and into the hole in a washer 40 introduced through said slot, the parts being so constructed and arranged that a washer introduced into said slot will first engage a portion of said actuating arm and move said arm to tension said spring against the washer 45 catcher arm and thereby cause said washer catcher arm to turn toward the coin slot and project its prong or dog yieldingly against the washer and finally into the hole therein, thereby arresting the washer in the coin-slot, 50 but permitting the washer to be withdrawn

from said slot due to the fact that said prong or dog has an upwardly inclined or tapered lower edge.

The invention will be fully understood from the detailed description hereinafter 60 presented, reference being had to the accompanying drawings, in which:

Fig. 1 is a bottom view of a coin-slot plate and my washer catcher mechanism applied thereto, Fig 1 being partly in section on the 65 dotted line 1—1 of Fig. 4, through the supporting casing for the washer catcher mechanism;

Fig. 2 is a like view of the same and illustrates a proper coin as being inserted 70 through the coin-slot and the washer catcher mechanism as having been actuated by said coin but not arresting the same, Fig. 2 illustrating the positions of the parts of the washer catcher mechanism when a 75 proper coin is being inserted through the coin-slot;

Fig. 3 is a corresponding view of the same illustrating a washer, in section, as having been introduced into the coin-slot, 80 the washer catcher mechanism being shown as having been actuated by the passage of the washer into the coin-slot and as having arrested the washer;

Fig. 4 is a vertical longitudinal section 85 through the coin-slot plate and washer catcher mechanism, taken on the dotted line 4—4 of Fig. 2;

Fig. 5 is a vertical transverse section 90 through the same, taken on the dotted line 5—5 of Fig. 2, and

Fig. 6 is a like section through the same, taken on the dotted line 6—6 of Fig. 3.

In the drawings, 10 designates the essential portion of a coin-slot plate, said plate 95 being formed with a vertical encompassing flange 11 defining between its opposite sides and ends the coin-entrance slot 12, as usual. The plate 10 is illustrative of a type of plate employed on machines whose mechanism is to be manually actuated upon the passage thereto of a proper coin. The coin-controlled mechanism of the machine is not shown, since this mechanism varies greatly and constitutes no portion of the present invention, which is confined to washer catcher mechanism applied at the lower side of the plate 10 and adjacent to the slot 12 for permitting the entrance of proper coins through said slot and arresting washers or 110

the like which it may be attempted to pass through the slot for the purpose of defeating the machine.

The washer catcher mechanism of my invention is preferably enclosed in a shallow box 13 which may be secured to the plate 10 by screws 14, and said mechanism comprises three main members, to-wit: an actuating arm 15, a washer catcher arm 16 and a leaf spring 17, said arms being bowed or curved toward each other at their shank ends and at said ends being overlapped and pivotally mounted for independent movement on a pivot stud or pin 18 secured to the bottom of the box 13.

The actuating arm 15 is elongated and extends along one side of the coin slot 12 and at its forward end has a deflected portion or member 19 which slantingly crosses one end 20 of said slot, as shown in Fig. 1, and at such crossing portion yieldingly obstructs the passage through the slot of a coin, washer or the like. The arm 15 is formed near its shank end with a stop-lug 20 which extends 25 toward and normally engages the washer catcher arm 16 and serves to space said arms apart in the normal position of the mechanism, as shown in Fig. 1.

The washer catcher arm 16 is less in 30 length than the arm 15 and lies along the opposite side of the coin-slot from the arm 15. The arm 16 at its forward end lies at about the transverse middle line of the slot 12 and thereat is formed with a pointed 35 prong or dog 21 which extends toward and stands at substantially a right angle to the said slot, the pointed end of the prong or dog normally being closely adjacent to the side edge of the slot and in position to be 40 projected transversely across the slot and into the hole of a washer, as 22 in Figs. 3 and 6, should a washer be passed into said slot. The forward end of the arm 16 normally bears against a stop pin 23, which is 45 rigid with the box 13 and serves to limit the movement of said arm 16 in a direction away from the slot 12. In the normal condition of the mechanism the lug 20 serves to limit the movement of the arm 16 toward the slot 50 12, and thus normally the arm 16 is positioned by and between the two stops 20, 23, the stop 20 being movable with the arm 15 when said arm is moved by an inserted coin 24 or washer 22 to allow the arm 16 to turn 55 toward the slot 12 and project its prong or dog 21 against such coin or washer and finally through the hole in the washer. The prong or dog 21 is reasonably pointed and has a flat upper surface and an upwardly 60 and outwardly beveled lower surface, as shown in Figs. 5 and 6, the said beveled lower surface permitting an arrested washer to be pulled upwardly from the coin slot and the said flat upper surface preventing an 65 arrested washer from being forced down

through said slot. The upward pull on an arrested washer against the beveled lower surface of the prong or dog 21 results in the arm 16 being turned in a direction away from the coin slot and in said prong or dog 70 thereby being caused to release the washer.

The leaf spring 17 has a free end 25 which is flexed freely against the side of the box 13 and an opposite end 26 which is rigidly secured to the arm 16, and said spring has an inward bend 27 bearing against the outer side of the arm 15, whence said spring curves around the shank ends of the arms 15, 16 without touching the same. The spring 17 is under tension and normally 80 presses the arm 15 to its operative position and causes the stop member 20 to press the arm 16 to its operative position against the stop 23, which arrests outward movement of said arm 16. The arm 16 and stop member 20 prevent undue inward movement of the arm 15, and hence both arms are normally held in their operative positions at the slot 12.

In the employment of the mechanism of my invention a coin 24 introduced through the slot 12 will move against the deflected end 19 of the arm 15 and turn said arm in a direction from the slot 12 and against the bend 27 in the spring 17, thereby further 95 tensioning said spring and withdrawing the stop 20 from the arm 16, with the result that the arm 16 will turn toward the slot 12 and project its prong or dog 21 against the face of the coin. The coin 24, not having a hole 100 in it, may be pressed through the coin slot in opposition to the yielding force exerted against it by the prong or dog 21. When a washer 22 is passed into the coin slot, the washer acts against the arm 15 the same as did the coin 24 and said arm is turned outwardly from the slot and the arm 16 is turned toward the slot and projects its prong or dog 21 against the face of the washer. When the washer has been moved inwardly 105 far enough to carry its hole into line with the prong or dog 21, said prong or dog will be instantly driven into said hole and across the coin slot and arrest the washer, as shown in Fig. 6. The washer 22 when arrested may 110 be withdrawn upwardly from the coin slot to clear the same but cannot be pressed downwardly from said slot, as hereinbefore explained.

When a proper coin 24 is being passed 115 through the coin slot 12, the arm 16 leaves the stop 23 to a limited extent, as shown in Fig. 2, and is prevented from having further movement toward the slot 12 by the engagement of the prong or dog 21 with the face of 120 the coin. When a washer 22 is passed into the coin slot 12 the hole in the washer leaves an unobstructed passage for the prong or dog 21 to cross said slot, as shown in Fig. 3.

In the construction of the washer catcher 125

mechanism of my invention, I have sought to provide a mechanism which is efficient and of such durable nature as to be capable of long public use without impairment. The 5 mechanism shown has been designed more particularly for use at the coin entrance slots of coin controlled mechanisms employed in connection with turnstiles situated in public places, as at the entrances of trans- 10 sit stations, at which intending passengers must deposit a five cent piece through the coin slot in order to free the turnstile and permit the passenger to turn the same and pass through.

15 What I claim as my invention and desire to secure by Letters Patent, is:

1. In a coin-controlled machine having a plate containing a slot for the entrance of coins into the machine, washer catcher 20 mechanism located at the reverse side of said plate adjacent to said slot comprising an actuating arm extending along one side of said slot and pivoted at its shank end and at its free end slantingly crossing one end 25 of said slot to be engaged by the edge of a coin or the like introduced into said slot, a washer catcher arm extending along the other side of said slot and pivoted at its shank end and at its free end having a 30 prong or dog extending therefrom toward and adapted to be projected across said slot, one of said arms having a stop normally engaging the other arm to keep said arms normally spaced apart, and spring means ten- 35 sioned against said actuating arm to yieldingly press the same to its operative position and against said washer catcher arm to turn it toward the coin slot when the actuating arm is turned outwardly from the slot by an 40 introduced coin or the like.

2. In a coin-controlled machine having a plate containing a slot for the entrance of coins into the machine, washer catcher mechanism located at the reverse side of 45 said plate adjacent to said slot comprising an actuating arm extending along one side of said slot and pivoted at its shank end and at its free end slantingly crossing one end of said slot to be engaged by the edge of a coin or the like introduced into said slot, a washer catcher arm extending along the other side of said slot and pivoted at its shank end and at its free end having a prong or dog extending therefrom toward and 50 adapted to be projected across said slot, said prong or dog having a flat upper surface and an upwardly and outwardly beveled lower surface, and spring means tensioned against said actuating arm to yieldingly press the same to its operative position and against said washer catcher arm to turn it toward the coin slot when the actuating arm is turned outwardly from the slot by an introduced coin or the like.

3. In a coin-controlled machine having a

plate containing a slot for the entrance of coins into the machine, washer catcher mechanism located at the reverse side of said plate adjacent to said slot comprising an actuating arm extending along one side of said slot and pivoted at its shank end and at its free end slantingly crossing one end of said slot to be engaged by the edge of a coin or the like introduced into said slot, a washer catcher arm extending along the other side of said slot and pivoted at its shank end and at its free end having a prong or dog extending therefrom toward and adapted to be projected across said slot, one of said arms having a stop normally engaging the other arm to keep said arms normally spaced apart, and spring means tensioned against said actuating arm to yieldingly press the same to its operative position and against said washer catcher arm to turn it toward the coin slot when the actuating arm is turned outwardly from the slot by an introduced coin or the like, said spring means being a leaf-spring bearing against the outer edge of said actuating arm and thence curving around the shank ends of both said arms and secured to said washer catcher arm.

4. In a coin-controlled machine having a plate containing a slot for the entrance of coins into the machine, washer catcher mechanism located at the reverse side of said plate adjacent to said slot comprising an actuating arm extending along one side of said slot and pivoted at its shank end and at its free end slantingly crossing one end of said slot to be engaged by the edge of a coin or the like introduced into said slot, a washer catcher arm extending along the other side of said slot and pivoted at its shank end and at its free end having a prong or dog extending therefrom toward and adapted to be projected across said slot, a stop to limit the outward movement of said washer catcher arm, said actuating arm having a stop member normally engaging said washer catcher arm to prevent inward movement thereof except when said actuating arm is moved by an introduced coin or the like and withdraws said stop member, and spring means tensioned against said actuating arm to yieldingly press the same to its operative position and against said washer catcher arm to turn it toward the coin slot when the actuating arm is turned outwardly from the slot by an introduced coin or the like.

5. In a coin-controlled machine having a plate containing a slot for the entrance of coins to the machine, a shallow box adapted to be secured to the reverse side of said plate below said slot and washer catcher mechanism carried by said box comprising an actuating arm extending along one side of said slot and pivoted at its shank end and at its

free end slantingly crossing one end of said slot to be engaged by the edge of a coin or the like introduced into said slot, a washer catcher arm extending along the other side 5 of said slot and pivoted at its shank end and at its free end having a prong or dog extending therefrom toward and adapted to be projected across said slot, and spring means tensioned against said actuating arm 10 to yieldingly press the same to its operative position and against said washer catcher arm to turn it toward the coin slot when the actuating arm is turned outwardly from the slot by an introduced coin or the like, said 15 spring means being a leaf-spring at its free end flexed against one side of said box and thence bent inwardly and engaging the outer edge of said actuating arm and thence curving around the shank ends of both said arms 20 and at its final end being fastened to said washer catcher arm.

6. In a coin-controlled machine having a plate containing a slot for the entrance of coins into the machine, washer catcher 25 mechanism located at the reverse side of said plate adjacent to said slot comprising an actuating arm extending along one side of said slot and pivoted at its shank end and at its free end slantingly crossing one end 30 of said slot to be engaged by the edge of a coin or the like introduced into said slot, a washer catcher arm extending along the other side of said slot and pivoted at its shank end and at its free end having a prong 35 or dog extending therefrom toward and adapted to be projected across said slot, said arms overlapping each other at their shank ends and mounted on a single pivot allowing said arms to have independent movement, 40 means restraining said washer catcher arm

from moving outwardly from normal position, means restraining said actuating arm from moving inwardly from normal position, and spring means tensioned against 45 said actuating arm to yieldingly press the same to its operative position and against said washer catcher arm to turn it toward the coin slot when the actuating arm is turned outwardly from the slot by an introduced coin or the like. 50

7. In a coin-controlled machine having a plate containing a slot for the entrance of coins into the machine, washer catcher mechanism located at the reverse side of said plate adjacent to said slot comprising an actuating arm extending along one side of 55 said slot and pivoted at its shank end and at its free end slantingly crossing one end of said slot to be engaged by the edge of a coin or the like introduced into said slot, a washer catcher arm extending along the other side of said slot and pivoted at its shank end and at its free end having a prong or dog extending therefrom toward and adapted to be projected across said slot, 60 means restraining said actuating arm from moving inwardly from normal position, means restraining said washer catcher arm from moving outwardly from normal position, and spring means tensioned against 65 said actuating arm to yieldingly press the same to its operative position and against said washer catcher arm to turn it toward the coin slot when the actuating arm is turned outwardly from the slot by an introduced 70 coin or the like. 75

Signed at New York city, in the county of New York and State of New York, this 20th day of June, A. D. 1922.

HARVEY GILES.
